United States Patent Office

Des. 182,815
Patented May 20, 1958

182,815

LABORATORY ELECTROMAGNET

Hugh J. Hall, Los Altos, Calif., assignor to Varian Associates, San Carlos, Calif., a corporation of California

Application June 5, 1957, Serial No. 46,496

Term of patent 14 years

(Cl. D26—1)

Fig. 1

Fig. 1 is a front perspective view of a laboratory electromagnet showing my new design.

Fig. 2 is a view in side elevation. The other side elevation of the electromagnet is the same.

Fig. 3 is a view in rear elevation.

I claim:

The ornamental design for a laboratory electromagnet, as shown and described.
